APPARATUS FOR BUILDING CONCRETE WALLS

Joseph Leo Ahart, Dow City, Iowa

Application February 20, 1947, Serial No. 729,697

10 Claims.

(Cl. 25—131)

1

This invention relates to an apparatus for continuous forming of monolithic concrete walls, and to a method of forming such walls. The apparatus and method utilize what is known as a "sliding form" which is moved along the wall as the wall is being constructed. Such sliding form will be referred to herein sometimes as a "mold."

The present invention is applicable to forming straight walls or curved walls, and either kind of any size and to forming straight and curved walls in combination.

There have been devices of this general nature, but they have all had serious handicaps. One notable objection to previous devices of this nature is that long vertical and horizontal reinforcing rods could not easily and effectively be embedded in the wall. The present invention overcomes this serious obstacle.

Another serious handicap common to present so-called "sliding forms" is that the elements of the sliding form must be loosened laterally from the green concrete before relocating to a new position. My invention provides for a form which is a sliding form in fact which requires no alteration during operation.

My novel method of constructing continuous concrete walls eliminates the necessity for allowing time for the concrete to harden in the construction process, thus eliminating the loss of valuable time.

It is therefore an object of my invention to provide an apparatus for constructing concrete walls which walls are made of highearly-strength concrete which hardens to a great degree soon after it is poured.

Another object of the present invention is the provision of a novel mold or sliding form for use in applying continuous adherent increments of the wall.

Another object of the invention is the provision of such a mold whereby successive increments of the wall become firmly bonded with each other.

A further object is the provision of such a new mold or sliding form which can be speedily placed in continuous successive positions for pouring adhering increments of the wall.

An additional feature of the invention is the adaptability of my novel mold to the inclusion of reinforcing steel rods in the concrete, which can be placed either horizontally or vertically in the wall.

A further object of this invention is the provision of novel track means and supporting structure therefor to be used in the construction of straight walls. The mold or sliding form above referred to is supported on tracks and movable therealong.

A still further object is the provision of said

2

supporting structure and tracks which can be elevated easily to accommodate added increments in the height of the wall.

A further object of the invention is the provision of a novel corner form which cooperates with the sliding form in forming corners of straight walls.

An additional object of the invention is the provision of novel track means for supporting the molds which can be made in great lengths, and the construction thereof is such that the long spans of tracks will not sag.

Still another object is the provision of aligning means for long spans of track for retaining the tracks in transverse alignment.

Still another object is the provision of a novel mold which, in forming the corners of straight walls, can be used on all the walls of the intended building, and cooperates with the corner form from both sides thereof in forming the corner of the wall.

Still another object of the invention is the provision of a novel mold such that a number of molds may be used on the supporting tracks at the same time.

Still another object of the invention is the provision of a novel mold by use of which openings, such as windows and doors, can be conveniently formed in the construction of the wall.

Still another advantage of the invention resides in the provision of a modified form of apparatus by which circular walls can be constructed by a continuous process.

Another object is the provision of a novel mold for use in constructing circular walls such that the molds can be curved to accommodate the curvature of different diameter circular walls.

With these and other objects in view, my invention consists in the construction, arrangement and combination of the various parts of my device whereby the objects contemplated are attained as hereinafter more fully set forth, pointed out in my claims, and illustrated in the accompanying drawings, wherein:

Figure 1 is a perspective view of a straight wall structure built according to my invention, together with the apparatus employed therefor;

Figure 2 is a perspective view, on an enlarged scale, of a portion of the building of Figure 1, showing in greater detail the tracks, supporting structure, and the mold;

Figure 3 is an enlarged perspective view of the corner mold, together with the means for supporting the ends of the tracks;

Figure 4 is an end view of the mold employed in forming a straight wall;

Figure 5 is a horizontal sectional view of a

corner of a wall showing the corner form and the
slidable mold;

Figure 6 is a horizontal sectional view of a portion of a straight wall showing the slidable mold in position for forming an opening in the wall;

Figure 7 is an elevational view of a portion of a wall showing the frame for forming an opening in the wall;

Figure 8 is an elevational view of a portion of the track for supporting the mold for forming a straight wall;

Figure 9 is an enlarged detail view of the means for connecting adjacent segments of the upper rail of the track shown in Figure 8;

Figure 10 is an enlarged detail view showing the means for connecting adjacent segments of the lower rail of the track Figure 8;

Figure 11 is a sectional view taken on line 11—11 of Figure 8;

Figure 12 is an enlarged detail view of the aligning means for retaining the track in transverse alignment;

Figure 13 is a view taken on line 13—13 of Figure 12;

Figure 14 is a horizontal section of a portion of a straight wall showing anchoring means for furring strips;

Figure 15 is a side elevational view of a modified form of structure for continuous construction of circular walls;

Figure 16 is a view taken on line 16—16 of Figure 15; and

Figure 17 is a view taken on line 17—17 of Figure 15.

The device of Figures 1 to 14

Referring now in detail to the drawings, and particularly to Figure 1, a plurality of upright supporting posts 12 are placed at the corners of the intended wall. Such posts 12 are spaced slightly outwardly of the corners, which spacing will be explained later. The posts 12 are suitably anchored in the ground and retained in plumb position by braces 14. Figure 1 shows a rectangular structure made up of straight walls 10, in which the longer sides have considerable length. In such cases aligning posts 16 are employed, being spaced appropriately between the supporting posts 12. The aligning posts 16 are suitably anchored in the ground and retained in plumb position by braces 18. The manner in which the aligning posts 16 are employed will be referred to in detail later.

Tracks 20 are supported on the corner supporting posts 12 along the sides of the intended wall. The tracks 20 include upper rails 22 and lower rails 24.

Means for supporting the tracks on the supporting posts 12 may be understood by reference to Figures 2 and 3. Each corner post 12 is preferably formed of suitable angle iron comprising legs 26 positioned with the concave side of the angle facing the corner of the wall, and the legs of the angle extended in the directions of the segments of the walls forming the respective corner.

A slidable hanger piece 28 of angle iron and of a short length is fitted in the corner post 12, the legs 30 of angle iron 28 fitting against the legs 26 of the post 12. The hanger piece 28 is slightly longer than the vertical distance between the rails 22 and 24 of the track. A securing strip 32 is welded to the hanger piece 28 across the open side, and the ends of the strip 32 are bent back around the outside of the post 12. The strip 32

secures the hanger piece 28 in the post 12 and permits vertical sliding thereof on the post.

Hooks 34 are welded to the inner surface of the legs 30 of the hanger piece 28, and are turned outwardly transverse to the plane of the legs 26 of the post 12. Such hooks 34 are provided at both the top and bottom of the hanger piece 28. The rails 22 and 24 of the track are then placed in the hooks 34 and are supported thereby.

10 There need be no additional anchoring means for the tracks 20 on the hooks 34, the tracks merely rest on the hooks. As noted in Figures 1 and 3 the track on one side may extend out beyond the corner and beyond the track on the other side.

15 This relation may obtain in each of the corners successively around the building, and by reason thereof the tracks need not be cut to accurate lengths.

The legs 26 of the post 12 are provided with a plurality of holes 36 spaced vertically a distance equal to the vertical increments to be added to the wall. The legs 30 of the hanger piece 28 are provided with holes in which are inserted pins 38 for adjusting the hanger piece 28 vertically on the post 12. The pins 38 may, if desired, be secured by cables or chains 40 to the slidable hanger piece 28.

An angle corner form 42 is secured to the slid-able hanger piece 28 by means of brackets 44 welded or otherwise suitably secured thereto. The legs of the angle corner form 42 are dis-posed at right-angles and are joined by a curved portion 46. The corner form 42 is spaced in-wardly from the hanger piece 28 and the post 12, as noted particularly in Figure 5, so that the legs of the form 42 form mold surfaces in constructing the wall.

The construction of the tracks 20 is such as to sustain themselves over long spans, and to sustain a load thereon. The rails 22 and 24 are of tubular construction as shown in Figure 11, and are preferably square in cross section. Figure 8 shows the track 20 in segments, and in each seg-ment the lower rail 24 is slightly shorter than the upper rail 22. Referring to Figure 9, the meeting ends of the adjacent segments of the rail 22 are cut back at the bottom as shown at 48. An insert 50 which may be tubular or solid as desired, is inserted in the meeting ends of adjacent seg-ments of the rail 22. The insert 50 is provided near its center with a button of weld material 52. The segments of the rail 22 are then fitted to-gether as shown in dot-dash line in Figure 9 and the cut-away portions 48 permit the ends of the segments of the rail to be fitted tightly together. The button of weld 52 prevents the insert 50 from extending too far into one or the other of the rail segments.

The segments of the bottom rail 24 are fitted together similarly to the upper rail, including the employment of inserts 50, but it will be noted from Figure 10 that there is a spacing as indicated at 54 between the ends of adjacent seg-ments. Brackets 56 are welded to the ends of the segments of the rails 24, and a bolt 58 is inserted through the brackets 56. The rails 22 and 24 are provided with vertical reinforcing mem-bers 60, welded between the rails, and dia-agonal thrust rods 62. The thrust rods 62 are provided with bolts for tightening them and aligning the rails of the track vertically. The separate sections of the track can be tightened together by the bolts 58. A load on the track puts the upper rail 22 in compression, which is resisted by the inter-engagement of the ends of

adjacent segments of the rail. The lower rail 24 is put in tension by a load, the segments thereof being retained in position by the bolts 58. The inserts 50 may be of any convenient length sufficient to retain the segments of the rails against transverse displacement.

The manner in which the aligning means retains long spans of track in lateral alignment may be understood from Figures 12 and 13. A sleeve 64 is slidable on the aligning post 16, and is provided with radial arms 66 one positioned above the other. Each arm 66 is provided with a hook 68 opening in opposite directions. The hooks 68 are hooked over the vertical supporting struts 60 whereby the track is held in lateral alignment by the aligning post 16. Such aligning posts 16 may be employed as desired, considering the lengths of the spans of track. The hooks 68 have a lateral extent greater than the width of the strut 60, to permit some degree of play when the track is angled vertically in the raising and lowering operations. Such spacings may be viewed in Figure 13.

The mold for forming the straight wall may be viewed in Figures 2 and 4, and designated generally at 70. The mold 70 includes an inner plate 72 and an outer plate 74. The plates 72 and 74 form molding surfaces substantially co-extensive and facing each other. The top, bottom and ends of the mold are open and unobstructed. The ends of the plate 72 are curved outwardly away from the other plate as shown at 76. The lower portion of the plate 74 is flat and vertical, and the upper portion is bent outwardly to form a baffle 78. Both plates 72 and 74 may be provided with horizontal reinforcing ribs 80 for strengthening purposes.

A pair of vertical members 82 are secured to the outer surface of the plate 74 by means of brackets 84. The members 82 are spaced apart and spaced inwardly a short distance from the ends of the molds. The vertical members 82 may be reinforced by diagonal pieces 86 if desired. Toward the top of the vertical members 82 are arms 88 extending horizontally over the mold and spaced upwardly from the top thereof. Brackets 90 are secured to the arms 88 and extend downwardly for securing the plate 72 thereto. The brackets 90 are secured to the arms 88 by means of bolts and the arms 88 are provided with a series of holes for adjustment of the plates 72 and 74 toward and away from each other. A pair of rollers 92 are mounted in the upper ends of the vertical members 82. The mold is supported by the track 20 by placing the rollers 92 on the upper rail 22. Retainer clips 94 retain the roller 92 on the track. The mold is positioned on the inside of the track and determines the line of the wall to be formed. The lower end of the vertical members 82 rest on the inside of the lower rail 24 of the track.

Use and operation of the device of Figures 1 to 14

The outline of the intended wall is marked off and the supporting posts 12 are placed outwardly of the corners thereof. This spacing is such that when the mold 70 is supported on the track 20, the mold is positioned over the intended wall, and the side plates 72 and 74 of the mold are spaced to the desired thickness of the wall. The hanger pieces 28 on the supporting posts 12 are positioned at the bottom of the posts so that the tracks 20 are in such position that the mold 70 rests on the ground, or substantially at the surface of the ground.

Concrete is poured in the mold 70 between the 75 wall.

plates 72 and 74, the baffle 78 assisting in directing the concrete into the mold. The mold 70 is open at the ends; this is a feature closely associated with the method of performing my new invention. A concrete mixture in plastic form is employed, as is usual in forming concrete walls. However, I have found that a mixture having a low water-to-cement ratio forms the best concrete. Such a mixture is readily adaptable to my method. A quantity of concrete of a mixture having a low water ratio retains itself more nearly in its original shape than mixtures having high water ratios. When the mold 70 is filled with a concrete mixture having a low water content it does not run out the ends of the mold. Such a mixture may also be known as "no-sag" mixture. It is therefore not necessary to allow time for setting of the concrete before sliding the mold along to a new position.

When the mold 70 is thus filled, the mold can be slid along the track 20 from such position to the next adjacent position at one end of the first increment. In such sliding action the plates 72 and 74 smooth the lateral surfaces of the increment just poured. When the mold is filled the operator eliminates all of the voids and air pockets in the concrete poured and no attempt is made to smooth the upper surface such as by a trowel. Although Figure 2 indicates that the upper surface is smooth, such illustration is merely a drafting representation.

I wish to point out an advantage of the feature just referred to. It was necessary to disassemble previous molds to move them to a new position, while the mold of my invention remains a rigid assembled unit throughout its operation and may be moved along to a new position without alteration in any manner.

In forming the corner of a straight wall building, my novel corner form is very effective. The mold is placed adjacent the corner post and the outside plate 74 of the mold is abutted against the adjacent leg of the corner form 42, as illustrated in Figure 5. The legs of the corner form 42 are of a length substantially equal to the thickness of the wall, so that when the outside plate 74 is abutted against the corner form the adjacent curved end 76 of the inside plate 72 is positioned adjacent the inner surface of the segment of the wall forming the other part of the corner. Concrete is then poured in the mold, and between the mold and the corner form 42. A corner in the wall is thus formed and the next step is to move the mold from the rail by lifting it from its position on one side of the corner and placing it on the track on the other side of the corner in abutting relation to the opposite leg of the corner form 42. Such position of the plates 72 and 74 is shown in dotted lines in Figure 5. The curved end 76 at the opposite end of the inner plate 72 fits against the inner surface of the corner. The curvature of the ends 76 of the inner plate 72 forms a rounded corner of the wall. Similarly, the rounded portion 46 of the corner form 42 forms a rounded surface on the outside of the corner.

When walls of different thickness are to be built, corner forms 42 having different length legs to correspond with the thickness of the wall, may be used. For this purpose the corner forms may be secured to the hanger piece 28 by means of bolts. The curved portion 46 and the ends 76 of the plate 72 may be made of any curvature desired for a curved finish of the corner of the

After one increment is poured completely around the wall, the hanger pieces 28 on the posts 12 are raised by removing the pins 38, sliding the brackets upwardly to the next hole 36 thereabove, and inserting the pins 38 in the new positions. The spacing of the holes 36 is the same as the height of one wall increment. In adjusting the hanger pieces 28, the corner forms 42, being secured thereto, are raised also and put in position for the next higher increment of the wall. The vertical extent of the corner mold 42 is the same as the plates 72 and 74 of the mold.

The vertical height of the side plates 72 and 74 of the mold is slightly greater than the vertical increment added, so that when the mold is raised to a higher position, the lower edges of the side plates are slightly below the upper edge of the lower increment. This insures proper alignment and smoothness of the side surfaces of the wall, and better bonding between the increments.

Obviously, if desired the upper and lower pairs of hooks 34 may be on separate pins and individually adjusted. In the latter case, the corner form 42 would be secured to one of the pairs of hooks.

An important feature of the present invention will now be evident, i. e., that long lengths of reinforcing steel rods can be placed in the walls in their formation. Figure 2 illustrates vertical rods 96 inserted in the walls. The molds 70 may be positioned on one side or the other of the rods 96, and to place the mold in position for the new increment it is lifted off the track and placed on the other side of the vertical rods. The rods 96 may be placed anywhere throughout the length of the mold since the mold has an open top. Similarly, horizontal reinforcing rods may be placed in the wall, such as indicated at 98 in Figure 5. The mold is open from end to end and therefore long lengths of horizontal reinforcing rods 98 may be employed.

Several molds 70 may be used at the same time on the track 20 on one level, to speed construction of the wall.

The mold plates 72 and 74 may be of any desirable material adaptable to forming into plates. In the present instance I preferably use aluminum to eliminate as much weight as possible, and because concrete does not adhere to aluminum readily. However, other materials may be used if desired.

Figure 6 illustrates a manner in which window openings can be formed in the wall. A frame 100 is placed on the surface of the particular increment at the height desired, and the mold plates 72 and 74 are moved up to and slightly beyond the side members of the form 100. After the upper level of the window opening is reached, a reinforcing steel plate 102 (Figure 7) is inserted and the next level of the wall is proceeded with the same as before.

In like manner, horizontal beams may be inserted in the wall by placing the ends thereof on the increment at the desired level and additional increments of concrete poured in place thereabove.

As illustrated in Figure 14, wedge shaped wooden blocks 104 may be inserted in the construction of the wall by placing them in the mold against the inner surface of the inside plate 72. When the mold is removed the exposed surfaces of the blocks 104 will be flush

with the inner surface of the wall, and may be utilized for securing furring strips along the wall. Another method of affixing securing elements in the wall, such as hooks or screws, is to insert such hooks or screws in the inner surface of the wall immediately after removing the mold therefrom and before the concrete has had sufficient time to set.

In adjusting the hanger pieces 28 vertically, it is not necessary to adjust them all in unison; each may be adjusted independently, and in such case the rails 22 and 24 of the tracks 20 merely ride up on the hooks 34. There is no binding of the rails 22 and 24 on the hooks in such movement.

In any such vertical adjustment of the tracks, the sleeves 64 on the aligning posts 16 merely slide up on the post 16. The hooks 68 on the aligning sleeves remain in constant engagement with the vertical truss pieces 60. When one corner of the track is elevated and the opposite end remains at its lower position, the track is disposed at an angle. Such angularity is also present in the vertical truss pieces 60 of the tracks, and due to the lateral play between the hooks 68 and the vertical truss pieces 60, such angularity is accommodated.

The tracks may be elevated by placing jacks under the binding strips 32 for raising the hanger pieces 28. A support for the jack may consist of a platform supported in the holes 36 in the post 12 below the hanger piece 28. Such platform may be raised for successive vertical positions of the hanger piece 28.

The thickness of the wall to be formed is determined by the spacing of the plates 72 and 74 of the mold. This spacing may be adjusted by moving the bracket 90 inwardly or outwardly on the arm 88 and placing the bolts in different holes. After the wall has reached the desired height, the last increment is of course smoothed with a trowel for affixing the roof.

The device of Figures 15, 16 and 17

A modified form of apparatus is illustrated in Figures 15, 16 and 17. The present form of apparatus is employed for building circular walls.

A vertical post 106 is supported by a base 108 placed at the center of the intended circular wall. A member 110 is slidably supported on the post 106 by means of collars 112. A ring 114 is secured to the bottom of the member 110. A pin 116 placed in one of the holes 118 in the post supports the member 110. The member 110 may be adjusted vertically on the post by placing the pin in different holes.

A pair of vertically aligned lugs 120 are formed on the member 110, and pivoted on the lugs 120 are tubular members 122 interconnected at their outer ends by a link 124. A tension spring 126 is secured to the member 110 toward the upper end thereof and to a bolt 128 secured to a bracket at the outer end of the lower tubular member 122. The tension of the spring 126 can be adjusted by the bolt 128, the spring serving to retain the tubular members 122 in horizontal position. Shafts 130 are slidably inserted in the tubular members 122 and held in position therein by set screws 132 threaded through the sleeves 122. The outer ends of the shafts 130 are secured together by plates 134, extending radially inwardly a considerable distance from the ends of the shafts 130. Welded to the upper edges of the plates 134 is another tubular piece 136. The

tubular piece 136 is preferably square in cross

section, and slidably mounted in the tubular piece 136 is still another tubular member 138 which is also square in cross section. A collar 140 provided with a set screw surrounds the tubular member 138 inwardly of the tubular piece 136 to limit outward sliding of the member 138. Secured to the outer end of the tubular member 138 is a depending yoke 142. A compression spring 141 surrounds the tubular member 138 between the tubular piece 136 and yoke 142, serving to bias the tubular member 138 outwardly in the piece 136. Secured as by welding to the lower end of the yoke 142 is a transverse channel piece 144 to which is attached a plate 146 forming one of the side plates of a mold. The plate 146 is provided with a longitudinal reinforcing strip 148 which is slidably secured at its ends in the ends of the transverse channel member 144. A set screw 150 is threaded through the channel member 144 midway between the ends thereof and engages the reinforcing strip 148. Adjustment inwardly of the set screw 150 bows the plate 146 inwardly at the middle. Slots may be provided in the ends of the channel member 144 to accommodate sliding pins in the ends of the reinforcing strip 148.

A tubular member 152, square in cross section, is telescoped in the tubular member 138 and extends radially outwardly beyond the mold plate 146. A set screw 154 is threaded through the outer end of the tubular member 138 for securing the member 152 in adjusted position. Secured to the outer end of the member 152 is a depending yoke 156 at the bottom of which is secured a transverse channel member 158. A mold plate 160 has secured thereto a longitudinal reinforcing strip 162 which is pivoted midway between its ends in the channel member 158. Set screws 164 are threaded through the extremities of the channel member 158 and engage the reinforcing strip 162. By adjusting the set screws 164 the outer mold plate 160 can be curved to conform to the curvature of the inner mold plate 146.

The two mold plates 146 and 160 can thus be curved to conform to the curvature of the intended wall.

Use and operation of the device of Figures 15, 16 and 17

The member 110 is lowered on the post 106 to a point where the mold plates 146 and 160 are substantially at the surface of the ground. Concrete is poured between the mold plates in the same fashion as with the previous form. After one increment is thus poured, the radius arm is swung about the post 106 so that the mold plates 146 and 160 are in a position for pouring a new increment adjacent the first. Another increment of concrete is then poured, and the process is continued until one increment in height is completed entirely around the wall. The member 110 is then elevated to the next position to raise the mold plates 146 and 160 to pour the next successive level. The mold plates 146 and 160 are preferably of a depth slightly greater than one increment, so that in pouring a new increment the lower edges of the mold plates are slightly below the upper edge of the previous increment below.

Windows can be formed in circular walls similar to the manner shown in connection with the straight walls. In swinging the radius arm about, it is desirable to move the mold plates out of position to avoid the frames for the win-

dow openings. The mold as a whole may be moved inwardly or outwardly by sliding the shafts 130 in the tubular sleeves 122. Also the thickness of the wall can be controlled by adjusting the mold plates toward and away from each other. By sliding the tubular member 138 in the sleeve 136, and sliding the member 152 in the member 138, various positions of the mold, and spacings between the mold plates, can be accomplished.

While I have herein shown and described a preferred embodiment of my invention, manifestly it is susceptible of modification and rearrangement of the parts without departing from the spirit and scope thereof. I do not, therefore, wish to be understood as limiting my invention to the precise form herein disclosed, except as I may be so limited by the appended claims.

I claim:

1. An apparatus for building a concrete wall, comprising, in combination, a plurality of vertical supports spaced along and adjacent to the outline of the intended wall, a track supported on and between said vertical supports, said track being disposed laterally offset from and adjacent to the path of the intended wall, and a mold cooperable with said track, said mold having a pair of spaced side plates and having its top, bottom and ends open, rollers on said mold laterally offset with respect thereto and detachably engageable with said track for supporting said mold thereon, said mold being disposed over the path of the wall, said mold being slidable along said track in a direction longitudinally of the mold, and means below and extending along the length of said track engageable by said mold and operative for retaining said mold in vertical position.

2. An apparatus for building a concrete wall polygonal in outline, comprising, in combination, a vertical support at each of the corners of the intended wall, tracks supported on and between said vertical supports, a mold adapted to be supported on and slidable along said tracks, said mold having a pair of spaced side plates, and an angle member on each of said vertical supports, the legs of each angle member extending in the directions of the segments of the wall forming the respective corner, and to an extent substantially equal to the spacing between said side plates, said angle members cooperating with said side plates to form an extension of said mold when the mold is adjacent thereto.

3. An apparatus for building a concrete wall polygonal in outline, comprising, in combination, a vertical support at each of the corners of the intended wall, vertically adjustable supporting means on each of said vertical supports, tracks supported between said vertical supports on said supporting means, a mold adapted to be supported on and slidable along said tracks, said mold having a pair of spaced side plates, and an angle member on each of said supporting means, the legs of each angle member extending in the directions of the segments of the wall forming the respective corner, and to an extent substantially equal to the spacing between said side plates, said angle members cooperating with said side plates to form an extension of said mold when the mold is adjacent thereto, said angle members, tracks and mold being movable vertically in unison responsive to vertical adjustment of said supporting means on said vertical supports.

4. An apparatus for building a concrete wall

11

polygonal in outline, comprising, in combination, a vertical support at each of the corners and on the outside of the intended wall, tracks supported on and between said vertical supports and adjustable vertically thereon, a mold adapted to be supported on said tracks and slideable therewith, said mold having a pair of spaced side plates disposed on opposite sides of the intended wall, said side plates being of substantially equal length, the side plate on the inner side of the intended wall having its ends curved outwardly away from the other side plate, and an angle member adjustable vertically on each of said vertical supports, the legs of each angle member extending in the directions of the segments of the wall forming the respective corner, and to an extent substantially equal to the spacing between said side plates of the mold, said angle members cooperating with the side plates of the mold to form an extension of the mold when the mold is adjacent thereto.

5. An apparatus for building a concrete wall, comprising, in combination, a plurality of vertical supports spaced along the intended wall, tracks supported on and between said vertical supports, a mold adapted to be supported on said tracks and movable therewith, and means on each of said vertical supports in longitudinal alignment with and cooperating with and forming an extension of said mold when the mold is adjacent thereto.

6. An apparatus for forming a concrete wall, comprising, in combination, a plurality of vertical supports spaced along the intended wall, tracks supported on and between said vertical supports, each of said tracks having a plurality of vertically spaced horizontal members, a mold having hanger means adjacent its top and offset laterally with respect thereto, said hanger means being engageable with one of said horizontal members of said tracks for supporting the mold thereon, the lower part of said mold bearing laterally against a horizontal member below said one horizontal member, whereby said lower horizontal member supports the mold in vertical alignment.

7. In a track structure for use in an apparatus for forming a concrete wall, a plurality of sections, each section being a self-contained unit, each section comprising a pair of vertically aligned horizontal members, truss members interconnecting said horizontal members, the upper horizontal members of each section being longer than the lower horizontal member of the same section, the adjacent ends of the upper horizontal members of successive sections being in abutting relation and in longitudinal alignment in the assembled track structure, the adjacent ends of the lower horizontal members of successive sections being spaced apart and in longitudinal alignment in the assembled track structure, means operable to retain adjacent upper horizontal members and adjacent lower horizontal members against transverse displacement, and means interconnecting adjacent lower horizontal members and placing them under tension.

8. In a track structure for use in an apparatus for forming a concrete wall, a plurality of sections, each section comprising a pair of vertically aligned tubular horizontal members, truss members interconnecting said horizontal members, the upper horizontal members of each section being longer than the lower horizontal member of the same section, the adjacent ends of the upper horizontal members of successive sections

12

being in abutting relation and in longitudinal alignment in the assembled track structure, the adjacent ends of the lower horizontal members of successive sections being spaced apart and in longitudinal alignment in the assembled track structure, inserts having portions slidably extending into adjacent ends of the upper horizontal members and in adjacent ends of the lower horizontal members for retaining them against transverse displacement, and means interconnecting adjacent lower horizontal members and placing them under tension.

9. An apparatus for building a concrete wall, comprising, in combination, a plurality of vertical supports spaced along the intended wall, said supports being angle shape in cross section, an angle shape track carrier vertically slideable in each support, means for retaining said track carriers in said supports, hooks extending outwardly from said track carriers laterally beyond said supports, said hooks being arranged in pairs with the hooks of each pair disposed at an angle with respect to each other, tracks detachably supported on said hooks between successive supports, and a mold detachably supported on and slidably along said tracks.

10. In a track structure for use in an apparatus for forming a concrete wall, a plurality of sections, each section comprising a pair of vertically aligned tubular horizontal members, truss members interconnecting said horizontal members, the upper horizontal members of each section being longer than the lower horizontal member of the same section, the adjacent ends of the upper horizontal members of successive sections being in abutting relation and in longitudinal alignment in the assembled track structure, the adjacent ends of the lower horizontal members of successive sections being spaced apart and in longitudinal alignment in the assembled track structure, inserts having portions slidably extending into adjacent ends of the upper horizontal members and in adjacent ends of the lower horizontal members for retaining them against transverse displacement, each insert having a projection limiting its movement into either of its associated horizontal members, and means interconnecting adjacent lower horizontal members and placing them under tension.

JOSEPH LEO AHART.
